(57) **CLAIM**

The ornamental design for a glove, as shown and described.

DESCRIPTION

FIG. 1 is a perspective back view of a first embodiment of a glove for a left hand showing my new design;

FIG. 2 is a perspective front view thereof;

FIG. 3 is a back view thereof;

FIG. 4 is a front view thereof;

FIG. 5 is a left side view thereof;

FIG. 6 is a right side view thereof;

FIG. 7 is a top view thereof;

FIG. 8 is a bottom view thereof;

FIG. 9 is a perspective back view of a second embodiment of a glove for a right hand, with all views being mirror images of the first embodiment of the left hand glove; and, FIG. 10 is a perspective view of the glove in use.

Long broken lines illustrate stitching on the glove. Short broken lines in FIG. 10 illustrate environment and form no part of the claimed design.
